CLAIM

The ornamental design for nestable container, as shown and described.

DESCRIPTION

FIG. 1 is a perspective view of an ornamental design for a nestable container showing our new design.

FIG. 2 is a top plan view thereof.

FIG. 3 is a left side elevation thereof, which is a mirror image of a right side elevation thereof.

FIG. 4 is a front elevation thereof, which is a mirror image of a rear elevation thereof.

FIG. 5 is a bottom plan view thereof.

FIG. 6 is an environmental view, depicting a number of the containers in a stacked condition; and,

FIG. 7 is an environmental view, depicting a number of containers in a nested condition.

The broken line showing of the upper container in FIG. 6 and the lower containers in FIG. 7 is for illustrative purposes only and forms no part of the claimed design.

1 Claim, 6 Drawing Sheets
